United States Patent Office

Des. 205,656
Patented Sept. 6, 1966

205,656

HOLDER FOR FOOD PAN FOR PETS

Tony Robert, 5701 Southwest Freeway, Houston, Tex.

Filed Oct. 18, 1965, Ser. No. 87,543

Term of patent 14 years

(Cl. D12—2)

Fig. 1

Fig. 2

I claim:

The ornamental design for a holder for food pan for pets, as shown and described.
